(57) **CLAIM**

The ornamental design for a camera housing, as shown and described.

DESCRIPTION

FIG. 1 is a front, right, and top perspective view of a camera housing showing our new design;

FIG. 2 is a back, left, and bottom perspective view thereof;

FIG. 3 is a front elevational view thereof;

FIG. 4 is a back elevational view thereof;

FIG. 5 is a left side elevational view thereof;

FIG. 6 is a right side elevational view thereof;

FIG. 7 is a top plan view thereof; and,

FIG. 8 is a bottom plan view thereof.

The dashed-dot lines form the boundary of the claimed design and the even dashed broken lines shown in the drawings are included for the purpose of illustrating portions of the camera housing that form no part of the claimed design.

There are two columns shown in broken lines that form no part of the claimed design with one column situated behind the conical structure while the other column is positioned in front of the conical structure depicted in FIGS. 2, 3 and 7.

1 Claim, 8 Drawing Sheets
